UNITED STATES PATENT OFFICE.

HORACE E. KENT, OF DORCHESTER, MASSACHUSETTS.

HEADLIGHT.

1,193,396.

Specification of Letters Patent.

Patented Aug. 1, 1916.

Application filed February 8, 1916. Serial No. 77,012.

To all whom it may concern:

Be it known that I, HORACE E. KENT, a citizen of the United States, residing at Dorchester, in the county of Suffolk, in the 5 State of Massachusetts, have invented a certain new and useful Improvement in Headlights, of which the following is a specification, reference being had to the accompanying drawings.

10 This invention relates to headlights of the class used commonly on automobiles, and the like vehicles, and my purpose is to provide a light, cheap and serviceable housing for the lamp and reflector of such headlights, as well as novel means for removably securing the front glass in such housings.

In order to explain my invention clearly I have provided the annexed drawings in which—

20 Figure 1 is a front elevation of a headlight embodying my present improvements and Fig. 2 is a side elevation of the same with the housing partly broken away to disclose the interior construction. Fig. 3 is a 25 detached, circumferential face view of a ring by means of which the front glass is removably secured in place in the reflector housing. Fig. 4 is a relatively enlarged, sectional, view of engaging portions of the 30 housing, the front glass, and the means for locking the said glass in the housing.

Referring to these drawings the letter *a* indicates the reflector housing, or outer shell, the same being formed of papier mâché, or 35 so called "indurated fiber", which is cheap, strong, light and serviceable, the reflector proper being denoted by the letter *b*. The papier mâché wall of the housing, surrounding the open front end of the housing, is reinforced, as at *a'* and is rabbeted interiorly as at *a''* to receive a metal ring *c* whose outer 40 face is formed with an annular channel in which is seated a ring *d* of felt, cork, leather or the like resilient packing against which is seated the glass *e* which serves as a closure for the otherwise open end of the housing *a*. The said housing is formed with 45 two or more holes *f* in each of which is located a spiral spring *g*, and the ring *c* is provided with a like number of pins or

screws *h* which enter the said springs when the several parts are assembled (see Fig. 4); the said springs then acting with a constant tendency to force the ring *c* outward.

Outside the disk of glass *e* is located the 55 retaining ring *i*, said ring being formed with two or more undercut notches *k* which serve, in connection with pins *m* in the housing *a*, as "bayonet joints" to lock the said ring in its home position in the housing. 60

In the operation of assembling the several described parts, the springs *g* are first dropped into the holes *f* and the ring *c* is placed in the rabbet *a''* with the pins *h* entered in the said springs. The disk *e* of 65 glass, is then placed in the rabbet, against the packing ring *d*, and the retaining ring *i* is placed against the glass and the assembled ring *c*, glass *e* and retaining ring *i*, are forced into the rabbet, against the resisting 70 force of the spring *g*, until the "bayonet joint" notches *k* can be interlocked with the pins *m*. The glass disk *e* is then firmly seated against the packing ring *d* which together with the springs *g* provide a yielding 75 support for said glass to relieve the rigidity, and danger of breakage, which would result if the glass was seated immediately in the rabbet *a''* and, at the same time a dust-proof joint is provided between the glass and the 80 reflector.

The customary ears *n*, (by means of which my described papier mâché housing may be supported on the vehicle) I provide by riveting to the opposite sides of said housing suitably shaped sheet metal plates, as 85 seen in Fig. 2.

My described headlight I find, in practice, is both serviceable and highly satisfactory.

Having thus described my invention, I 90 claim as new and wish to secure by Letters Patent:—

A headlight comprising, in combination, a papier mâché housing rabbeted at its open end, springs in said rabbet, a packing ring 95 seated on said springs, a disk of glass seated on said packing, and means for removably securing the said glass in said rabbet.

HORACE E. KENT.
